UNITED STATES PATENT OFFICE

WILLIAM E. VAN DORN, OF CHICAGO, ILLINOIS.

CORRUGATED STEEL END FOR GONDOLA CARS

Application filed March 9, 1921. Serial No. 450,993.

To all whom it may concern:

Be it known that I, WILLIAM E. VAN DORN, a citizen of the United States, residing at Chicago, county of Cook, State of Illinois, have invented a certain new and useful Improvement in Corrugated Steel Ends for Gondola Cars, and declare the following to be a full, clear, and exact description of the same, such as will enable others skilled in the art to which it pertains to make and use the same, reference being had to the accompanying drawings, which form a part of this specification.

My invention has for its primary object to produce a steel end for gondola cars which shall be simple in construction, capable of being easily applied, and which shall possess great strength and rigidity and have the capacity of reinforcing the sides of the car body.

The various features of novelty whereby my invention is characterized will hereinafter be pointed out with particularity in the claims; but, for a full understanding of my invention and of its object and advantages, reference may be had to the following detailed description taken in connection with the accompanying drawing, wherein:

Figure 1 is an end elevation of a gondola car provided with an end arranged in accordance with the present invention;

Fig. 2 is a top plan view of said end and fragments of the sides of the car body;

Fig. 3 is a section taken approximately on line 3—3 of Fig. 1; and

Fig. 4 is a section taken approximately on line 4—4 of Fig. 1.

Referring to the drawing, 1 represents a floor plate and 2, 2 the sides of a gondola car. The car end is made of corrugated sheet metal having flat portions such, for example, as the flat marginal portions, 3, 3, which establish the normal plane of the sheet; these flat portions being vertical in the assembled car body. The end may be made in the form of a single panel or out of a plurality of panels; there being, in the arrangement shown, two panels arranged side by side and having at their meeting edges flat marginal portions, 4, flanged outwardly as indicated at 5. Rivets, 6, unite

the flanges and form them into a central strengthening rib or post for the end. The flat marginal portions, 3, are provided with rearwardly-projecting flanges, 7, 7, which overlap the car sides and are fastened thereto in any suitable manner as, for example, by means of bolts, 8. The top and bottom marginal portions of the sheet are left flat and are bent outwardly to form flanges, 9 and 10, respectively; the flange 10 resting on the floor plate and being fastened thereto by means of rivets, 11, or the like.

The corrugations extend along vertical lines and preferably fill substantially the entire area of the end, merging one into the other so that in transverse section the sheet has a sinuous configuration. Furthermore, the corrugations are bent so that while their elements lie in vertical planes, they are not in the form of straight lines from top to bottom. In the arrangement shown, each corrugation is made up of two straight sections arranged end to end; the upper section, 12, starting just below the upper flange on the inner side of the normal plane of the sheet and extending downwardly and outwardly to a point about midway between the floor and the top of the car body, while the lower section, 13, begins at the foot flange, 10, also on the inner side of the normal plane of the sheet, and extends upwardly and outwardly until it meets the upper section. The lower ends of the corrugations are secured to the floor plate by suitable attaching devices secured thereto at the points farthest removed from the normal plane of the sheet and extending downwardly approximately parallel with the elements of the lower sections of the corrugations so as to make each corrugation in effect a post rigidly secured at its base to the floor plate and rising upwardly therefrom. In the arrangement shown, there is an individual L-shaped attaching piece, 14, between each corrugation and the floor plate, one arm being riveted to the corrugation by means of a rivet, 15, and the other arm being riveted to the floor plate by means of a rivet, 16.

On top of the upper flange, 9, is a cap plate, 17, wider at the middle than at the ends, the cap plate having a part, 18, ex-

ending inwardly and downwardly in contact with the extreme upper ends of the corrugations; the members 17 and 18 being riveted respectively to the flange 9 and to the corrugations. The cap plate is provided at its ends with rearward extensions, 19, overlying and in any suitable manner secured to the sides of the car. Where the sides are provided with longitudinal protecting plates, 20, lying upon their upper edges, the extensions may conveniently be riveted to these plates. Furthermore, the extensions 19 are preferably connected with the downwardly and rearwardly inclined part, 18, by means of webs, 21, so that the parts 17, 18 and 19 mutually reinforce each other.

While I have illustrated and described with particularity only a single preferred form of my invention, I do not desire to be limited to the exact structural details thus illustrated and described; but intend to cover all forms and arrangements which come within the terms employed in the definitions of my invention constituting the appended claims.

I claim:

1. A sheet metal panel having flat portions establishing the normal plane of the sheet and parallel corrugations each comprising two straight sections arranged end to end and so disposed that the meeting ends of the two sections of each corrugation lie on one side of said plane and the other ends lie on the opposite side of said plane.
2. A sheet metal car end having vertical flat portions establishing the normal plane of the sheet and parallel corrugations each comprising two straight sections lying one above the other and arranged end to end, the meeting ends of the sections of each corrugation being located on one side of said plane and the other ends being located on the other side of said plane.
3. A sheet metal car end having vertical flat portions establishing the normal plane of the sheet and parallel corrugations each comprising two straight sections lying one above the other and arranged end to end, the meeting ends of the sections of each corrugation being located on the outer side of said plane and the other ends being located on the inner side of said plane.
4. A sheet metal car end having vertical flat portions establishing the normal plane of the sheet and parallel corrugations each comprising two straight sections lying one above the other and arranged end to end, the meeting ends of the sections of each corrugation being located on the outer side of said plane and the other ends being located on the inner side of said plane, the upper and lower marginal portions of said end being flanged outwardly.

5. In combination, a car floor plate, a sheet metal end arranged above said plate and having its lower end bent outwardly to form a flange resting on said plate, said end having corrugations extending upwardly and outwardly from points on the inner side of the sheet and near the bottom thereof to points on the exterior of the sheet at a higher elevation, and attaching plates lying on the inner side of said end and secured respectively to the lower ends of said corrugations and to said plate.

6. In combination, a car floor plate, a sheet metal end arranged above said plate and having its lower end bent outwardly to form a flange resting on said plate, said end having corrugations extending upwardly and outwardly from points on the inner side of the sheet and near the bottom thereof to points on the exterior of the sheet at a higher elevation, and narrow L-shaped plates lying on the inner side of said end and each having one arm attached to the lower end of one of said corrugations and its other arm attached to said plate.

7. In combination, a car floor plate, a sheet metal end arranged above said plate and having its lower end bent outwardly to form a flange resting on said plate, said end having approximately vertical corrugations the lower ends of which lie on the inner side of the plane of the sheet, and means connecting the lower ends of the corrugations to said floor plate on the inner side of said plane.

8. A sheet metal car end having vertical flat portions establishing the normal plane of the sheet and parallel corrugations each comprising two straight sections lying one above the other and arranged end to end, the meeting ends of the sections of each corrugation being located on the outer side of said plane and the other ends being located on the inner side of said plane, the upper marginal portion of said end being bent outwardly to form a flange, and a metal cap lying upon and secured to said flange.

9. The combination with the sides of a car, of a sheet metal end engaged with said sides and having vertical flat portions establishing the normal plane of the sheet and parallel corrugations each comprising two straight sections lying one above the other and arranged end to end, the meeting ends of the sections of each corrugation being located on one side of said plane and the other ends being located on the other side of said plane, the upper marginal portion of said end being bent outwardly to form a flange, and a cap plate secured on said flange and having extensions projecting rearwardly into engagement with said sides.

10. In combination, a car floor plate, a sheet metal end arranged above said plate

and having an upright corrugation therein, the lower end of said plate being bent laterally toward the opposite side of the sheet from that on which the corrugation lies to form a flange, means securing said flange to said floor plate, a part secured to the lower end of said corrugation and extending down- wardly to said floor plate in a manner to form a continuation of the corrugation, and means for securing the lower end of said part to said floor plate.

In testimony whereof, I sign this specification.

WILLIAM E. VAN DORN.
